1. A milk receptacle for calves or the like having an open end and a closed end, the latter being engageable with a supporting plate, the receptacle being provided with a substantially rectangular cover plate which is positionable on the open end of the receptacle, the cover plate having a circular depression in its center, the receptacle being provided with a spout on one side, the spout being provided with a nipple, the nipple being removably receivable in the depression of the cover plate, the cover plate being provided with an angle bracket which is adjustably mounted on a screw secured to the receptacle, the angle bracket being pivotally attached to a strap which is secured to the receptacle, the strap being pivotally attached to a transverse rod, the rod being secured to the receptacle, the angle bracket being pivotally attached to a cam which is pivotally attached to a bracket secured to the cover plate, the cam being provided with a notch which is engageable with the rod.

UNITED STATES PATENT OFFICE

CALF FEEDER

Francis J. Haberkorn, Dalton, Wis.

Application January 14, 1949, Serial No. 70,906

3 Claims. (Cl. 119—71)

1

This invention relates to new and useful improvements and structural refinements in calf feeders, and the principal object of the invention is to facilitate convenient and expeditious refilling of the feeder when the contents thereof become exhausted.

This object is achieved by the provision of a feeder which includes in its construction a pair of plates, a receptacle removably receivable between the plates, and means for clamping the plates against the ends of the receptacle in such manner that the latter may be readily removed for cleaning or refilling purposes.

An important feature of the invention, therefore, resides in the particular clamping means herein utilized, and another feature of the invention lies in the provision of means for supporting or suspending the receptacle in an inclined position so that the contents thereof may freely gravitate into an outlet spout and discharge nipple.

Some of the advantages of the invention reside in its simplicity of construction, convenience of operation and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a side elevational view of the invention in its inverted position and in readiness for use.

Figure 2 is a side elevational view of the invention in an upright position, the same being partially broken away so as to reveal its construction.

Figure 3 is a top plan view of the subject shown in Figure 2, and

Figure 4 is an elevational view taken in the direction of the arrow 4 in Figure 2.

Like characters of reference are employed to designate like parts in the specification and throughout the several views.

Referring now to the accompanying drawings in detail, the invention consists of a calf feeder designated generally by the reference character 10, the same embodying in its construction a substantially rectangular supporting plate 12 which is provided at one edge thereof with a pair of laterally projecting, angulated suspension hooks or lugs 14 whereby the entire device may be suspended from a staple-shaped bracket or brackets 16 provided upon a wall 18.

2

A milk receptacle 20 has an open end 22 and a closed end 24, the latter end being engageable with the supporting plate 12 substantially as shown. A substantially rectangular cover plate 26 is positionable on the open end 22 of the receptacle 20, for which purpose the plate 26 is formed with a circular depression 28 so as to receive the open end or edge portion of the receptacle as is best shown in Figure 2. It may be explained in this connection that while the plates 12, 26 are rectangular, the receptacle 20 may be cylindrical, and an annular gasket 30 is positioned in the depression or recess 28 of the plate 26 so as to assure a leak-proof fitting of the plate on the receptacle when the entire device is inverted as will be hereinafter described.

The cover plate 26 is formed integrally with an outlet spout 32 on which is removably receivable a suitable nipple 34, and the spout 32 may also be provided in one side thereof with a small air vent 36. The nipple 34 is formed from rubber, or the like, and if desired, a hook 38 may be suitably secured to the spout 32 for the purpose of receiving a fabric nipple (not shown) which may be superimposed on the rubber nipple and saturated with milk so that the feeder may attract the attention of calves and encourage them in feeding.

A pair of screws 40 are secured by nuts 42 in suitable apertures provided in the plate 12 at diametrically opposite sides of the receptacle, and an angle bracket 44 is adjustably mounted on each screw 40 by a pair of lock nuts 46. Each of a pair of clamping straps 48 is pivoted as at 50 to one of the brackets 44, the straps 48 extending adjacent opposite sides of the receptacle 20 and projecting beyond the receptacle, at which point they are secured together by a transverse rod 52 equipped with lock nuts 54.

A pair of cams 56 are pivotally attached to suitable brackets 58 which, in turn, are secured to the cover plate 26, the pivotal attachment of the cams to the brackets being indicated at 60. It is to be also noted that the cams 56 are provided with suitable finger pieces 62 whereby they may be conveniently actuated.

The cams 56 are formed with notches 64 to engage the rod 52, and it will be noted that by virtue of the pivots 50 the rod 52 together with the straps 48 may be swung to one side as indicated at 66 in Figure 2, so that the receptacle 20, after being filled, may be placed on the plate 12 in an upright position. The plate 26 may then be applied to the receptacle and the members 48, 52 swung to a position wherein the cam notches 64 may be engaged with the rod 52 so as to draw

the rods 40 upwardly, thus tightly clamping the plate 12 against the bottom 24 of the receptacle and simultaneously clamping the plate 26 against the open end 22 of the receptacle, substantially as shown.

The nipple 34 may then be applied to the outlet spout 32 and the entire device may be inverted to a position shown in Figure 1, and the hooks 14 may be engaged with the staple or staples 16, so that the entire feeder is supported on the wall 18. It is to be noted in this connection that the plate 12 is substantially longer than the plate 26, so that the receptacle 20 is supported in an inclined position and the contents thereof are free to gravitate into the outlet spout 32. Moreover, by virtue of the two suspension hooks 14 and by virtue of the straight edge 68 of the plate 26, the feeder is prevented from rocking from side to side when the animals come into contact therewith, inasmuch as the hooks 14 engage the staple or staples 16 at spaced points and the straight edge 68 engages the wall 18 along its entire length, as will be clearly apparent.

When the contents of the feeder are emptied, the receptacle 20 may be refilled by simply releasing the cams 56, disengaging the rod 52 from the notches 64, and thereafter removing the cover plate 26, this, of course, being effected after the feeder has been removed from the wall 18 and returned to its upright position as shown in Figure 2.

It is to be noted that the rod 52 will function as an effective bail for carrying the entire device. By virtue of the nuts 46, the position of the brackets 44 on the bolts 40 may be adjusted to assure proper engagement of the cams 56 with the rod 52.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. A calf feeder comprising a supporting plate, a receptacle having an open end, a closed end on said receptacle in engagement with said supporting plate, a cover plate provided at the open

end of said receptacle, an outlet spout on said cover plate, a pair of clamping straps extending exteriorly along the diametrically opposite sides of said receptacle, said straps being anchored at one end to said supporting plate and projecting beyond said cover plate, a transverse rod connecting together the projecting ends of said straps, and a pair of locking cams rotatably mounted on said cover plate, said cams being formed with notches to releasably engage said rod, whereby said plates may be clamped against the respective ends of said receptacle upon actuation of said cams.

2. The device as defined in claim 1 together with means for adjustably connecting said straps to said supporting plate.

3. A calf feeder comprising: a receptacle, said receptacle being closed at one end and open at the other end, a supporting plate engaging said closed end, a pair of straps anchored to said supporting plate and in juxtaposition to the side wall of said receptacle, a transverse rod extending across said open end and connecting said straps at the ends remote from the supporting plate, a cover plate having an outlet spout and positioned between said rod and said open end, a pair of cams pivotally mounted on said cover plate and having notches therein, said cams each being provided with finger portions by which the cam is adapted to be manually actuated and which are adapted to engage the cover plate when in one position, said transverse rod being engaged in said notches, and said cam notches when in locked position being located between the pivotal axis of said cam and said finger portion whereby said cover plate is locked in sealed relation to said receptacle.
